Patented June 10, 1975

235,304

MEAT TENDERIZER

Sylvan Greenberg, 111 E. 85th St.,
New York, N.Y. 10028

Filed Aug. 30, 1973, Ser. No. 392,979

Term of patent 14 years

Int. Cl. D7—04

U.S. Cl. D7—101

FIG.1

FIG.3

FIG.2

FIG. 1 is a side elevational view of a meat tenderizer showing my new design, the sides not shown being similar in appearance to that shown;

FIG. 2 is a bottom view thereof; and

FIG. 3 is a top view thereof.

I claim:

The ornamental design for a meat tenderizer, as shown and described.
